UNITED STATES PATENT OFFICE.

CHARLES C. MALTON, OF WORCESTER, MASSACHUSETTS.

DESIGN FOR A GAS-STOVE.

SPECIFICATION forming part of Design No. 34,490, dated May 7, 1901.

Application filed March 20, 1901. Serial No. 52,112. Term of patent 7 years.

To all whom it may concern:

Be it known that I, CHARLES C. MALTON, a citizen of the United States, residing at Worcester, in the county of Worcester and State of Massachusetts, have invented and produced a new and original Design for Gas-Stoves, of which the following is a specification, reference being had to the drawings forming a part thereof.

My invention relates to "gas-stoves" or "gas-ranges," so termed.

The leading or material feature of my design consists of a body or top with openings therein, through one of which four parallel pipes appear in the same horizontal plane, and the two inner pipes connected together at one end and each connected at the other end with one of the outer pipes.

Referring to the drawings, Figure 1 is a perspective view of a gas-stove, showing my design; and Fig. 2 is a plan view of the stove shown in Fig. 1.

In the accompanying drawings, A is the body or top of a gas-stove of substantially square shape and having three openings B, B, and C therein, two of which, B B, are shown as circular, and one, C, as oblong or oval, and through the oblong or oval opening C four parallel pipes D appear in the same horizontal plane, and the two inner pipes connected together at one end and each inner pipe connected at its other end with one of the outer pipes.

A perforated plate or grate E is shown over each of the openings B, B, and C.

What I claim is—

The design for a gas-stove, substantially as shown and described.

CHARLES C. MALTON.
